UNITED STATES PATENT OFFICE.

EMILIUS C. F. HARTMANN, OF SALT LAKE CITY, UTAH.

DESIGN FOR A RADIO LOUD SPEAKER.

Application filed April 5, 1926. Serial No. 17,178. Term of patent 7 years.

To all whom it may concern:

Be it known that I, EMILIUS C. F. HARTMANN, a citizen of the United States, residing at Salt Lake City, in the county of Salt Lake and State of Utah, have invented a new, original, and ornamental Design for a Radio Loud Speaker, of which the following is a specification, reference being had to the accompanying drawing, forming part thereof.

The figures are respectively: Figure I a top plan view; and Figure II a side elevation view partly in section.

I claim:

The ornamental design for a radio loud speaker as shown.

EMILIUS C. F. HARTMANN.
